(57)

CLAIM

The ornamental design for a sports equipment rack, as shown and described.

DESCRIPTION

FIG. 1 is a top isometric view of a sports equipment rack showing the design;

FIG. 2 is a bottom isometric view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines form no part of the claimed design.

1 Claim, 7 Drawing Sheets
